(57) **CLAIM**

The ornamental design for a waffle iron, as shown and described.

DESCRIPTION

FIG. 1 is a front, right perspective view of a waffle iron, in a position of use with the lid open;

FIG. 2 is bottom, front, right perspective view thereof;

FIG. 3 is front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a front view thereof, in a position of use with the lid open;

FIG. 10 is a left side view thereof, in a position of use with the lid open; and,

FIG. 11 is a right side view thereof, in a position of use with the lid open.

The broken lines in the drawings are included for the purpose of illustrating subject matter that forms no part of the claimed design.

1 Claim, 9 Drawing Sheets
